UNITED STATES PATENT OFFICE.

JOHN A. BALL, OF GRASS VALLEY, CALIFORNIA.

DREDGING-MACHINE.

SPECIFICATION forming part of Letters Patent No. 530,675, dated December 11, 1894.

Application filed February 11, 1892. Serial No. 421,156. (No model.)

To all whom it may concern:

Be it known that I, JOHN A. BALL, a citizen of the United States, residing at Grass Valley, in the county of Nevada and State of California, have invented certain new and useful Improvements in Dredging-Machines; and I do hereby declare that the following is a full, clear, and exact description thereof.

This invention relates to apparatus for dredging and excavating material to form channels, canals, &c., of proper depth, and for elevating or conveying such dredged or excavated material above the water, and discharging and conveying it to any desired point of delivery near or remote from the location from whence it was taken.

My invention belongs principally to the class of dredging apparatus known as chain and bucket dredgers, in which the endless chains and buckets, continuously driven by suitable machinery and carried by a hull having a side sweep or oscillation, cuts the material, carries it above the water, and discharges it into or upon some form of a conveyer.

My present invention relates particularly, first, to improvements in the means for imparting to the hull of the dredge, and the endless chain and bucket or any other excavating device carried by it, the necessary side sweep or oscillation, as well as the forward movement required as the work progresses; secondly, in the novel and improved means for supporting and adjusting the chain of buckets; thirdly, in a new and improved apparatus, to which the excavated material is delivered from the buckets, and by which it is discharged at any point near or remote; fourthly, to certain improvements in the buckets themselves, and their attachment to the endless traveling chain; finally, to various details of construction, which need not be particularly specified here, but which are fully hereinafter described, and claimed, and are shown in the accompanying drawings, in which like letters represent like parts.

In the drawings—Figure 1 is a longitudinal section taken centrally through the hull of the dredge. Fig. 2 is a plan view. Fig. 3 is an end elevation. Fig. 4 is a side view of two of the buckets on an enlarged scale showing their connection to the chain, at the upper sprocket wheel. Fig. 5 is a front view of one

of the buckets. Fig. 6 is a plan view of the chain. Fig. 7 is a side view of a part of the carrier or draper, the track supporting it, and one of the sprocket wheels. Fig. 8 is a plan view of the carrier or draper. Fig. 9 is a broken longitudinal section of the chain which supports the draper. Fig. 10, is a detail view showing one pair of the channel tracks for the endless chains.

In the drawings, A represents the hull of the dredge and the line $x-x$ the water line. The depth of the water, and the face of the excavation being made, are plainly shown in Fig. 1, where the buckets are represented as working upon and up an incline from which they cut slices of the earth or material and discharge them, while the hull of the dredge swings across the channel.

The hull of the dredge, may be of any desired construction adapted to contain the engines and boilers for operating the entire apparatus, and having a well B through which the chains and their buckets pass downward empty and upward loaded.

The engine is indicated at C and may be of any ordinary construction capable of affording power enough to operate the dredging apparatus, and the delivery apparatus, and give the hull the required side sweep or oscillation across the channel while the dredge is at work.

The hull A has above it, and carried by it, suitable uprights and cross-beams to properly support all the working parts. At one end the hull is cut away centrally, to form the well B (shown in Figs. 1 and 2) for the reception of the adjusting ladders F and G which ladders, together with the hoist H, support and adjust the face-ladder E relatively to the face of the excavation. The said face ladder is constructed and intended for the support of the chains and buckets while on their upward course only, and not for their support both downward and upward as in the common use of endless chain and bucket ladder supporting frames. Therefore I use the term "face ladder" instead of "ladder" simply, in describing this part of my invention and in setting forth my claims to the same. By this construction I accomplish my object, which is to provide means by which the buckets may begin to cut and fill at the bottom of the

excavation, cutting thin strips from off the surface of the excavation for the whole distance from the bottom to the top; and by which the buckets continue on their round as hereinafter described so as to deliver the material at or near the central point of oscillation and to any desired height. It is more practical to connect pipes or carriers for conveying the material to the shore, at a point on the dredge near the center of oscillation, than at a point on the dredge distant from it.

The face ladder is composed of angle and channel iron of sufficient strength to carry the chain and buckets, and bear the strain caused by the buckets cutting the material. On the under side of the face ladder are channel tracks similar to those described in my Patent No. 299,945, dated June 10, 1884, and as shown in Fig. 10, which carry the chains and buckets upon the wheels 1, within said channel upward.

The chains are carried on the wheels 1 within said chains, upon and through the channel tracks, which sustain the buckets and thus cause them to travel on their proper course in a rigid manner. The endless chains referred to, are extended over the sprocket wheels 2 which are fast on a driven shaft 4; and the chains carrying the buckets, pass downward from said sprocket wheels upon stationary tracks 5 composed of angle iron which are bolted to the frame on the dredge, these tracks terminating near the well B. As the buckets come to the lower end of the face ladder where they begin to cut the material, the chains run through the channel tracks 6 before mentioned, shown in Fig. 10, and thence over the spools or flanged wheels, 31, at the upper end of the face ladder and on to the upper adjusting ladder F, said two ladders being pivoted together at 7. The chains are carried through similar channel tracks attached to the upper adjusting ladder F. From thence the chains are carried over the said upper stationary tracks to the sprocket or driving wheels. At the point where the upper adjusting ladder F and upper stationary tracks 8 join, is a suitable device, such as screw 9 for moving outward or inward and withholding the adjusting ladder for the purpose of regulating the tension of the chains, and to lower or raise the upper end of the face ladder.

The lower adjusting ladder G has no tracks attached to it, and is only used to regulate the depth of the excavation by raising or lowering the rear and lower end of the face ladder, which may be done by any other mechanical means, but preferably by a rack on the ladder, and pinions on a supported cross-shaft 10 driven preferably by a worm gear. (Not shown.) Any other mechanical means may be used by which the chains and buckets may be carried over or around spools or guides, so as to pass around the same course from the lower to the upper end of the face ladder, and yet be within the scope of my in-

vention. As the chains and buckets thus traverse the above described round, the buckets cut or plane off the material from the inclined surface of the excavation, each bucket commencing to cut and fill at the bottom of the excavation and ending at the top. The material falls loosely into the buckets and is elevated to and over in to the hopper 11, or upon a chute or carrier. As shown it is delivered upon an improved draper or carrier I, to be hereinafter described.

The principal advantages gained by this improved face-ladder is that the excavation is made complete from bottom to the top of the excavation without requiring the raising or lowering of the excavating apparatus while the channel tracks provide for the buckets, edge or share to pass rigidly upon their proper course. It also completes the full desired width of the channel. It likewise also provides for adjusting the said excavating apparatus, so as to plane or cut from the face of the excavation at any desired incline, at the sides of, or at the face of the channel.

The bridge frame D, shown in Figs. 1, 2 and 3, is a transverse structure resting, when not anchored, upon the hull of the dredge and pivotally attached to it. To the bridge frame, are attached rollers or wheels which roll upon tracks, 12 and 13 fastened to the deck of the hull and which carries the weight of said bridge frame, allowing it to oscillate upon the king bolt or pivot 14.

When the machine is at work, and is being swung from one side of the channel to the other, the spuds 15, 15 at the opposite ends of the frame are let down through eyelets 16 attached to the bridge frame. Said spuds are thrust down into the bed of the channel, and anchor the said bridge frame so that the hull of the dredge, being pivotally attached to said bridge frame, is left to swing freely about the king bolt; and I effect the regulation of this oscillation of the hull of the dredge in the following described manner: As best shown in Fig. 2, a chain or rope 17 is attached to the sides of the hull by the eyebolt 18 and passes in a groove to and around a gipsy 19, and thence to eyebolt 20 where the other end of the chain is fastened to the hull. The said gipsy 19 is attached to the bridge frame, and its shaft is made to turn either way in the application of power so as to draw on one or the other of said eyebolts, causing the hull to swing one way or the other upon said king bolt at the will of the operator.

Any other known mechanical means may be used to swing the dredge from side to side from the bridge-frame to which it is pivotally attached, and yet be within the limits of my invention.

When the dredge has been made to swing across from one side of the channel to the other, it is necessary to advance forward on the excavation for a new cut, before commencing to swing back across the channel again. To accomplish this operation I oper-

ate the screw device 28 so as to bring one of the auxiliary spuds 21 (whose supporting frames 29 are pivotally attached near the king bolt), as near the bridge spud on the side 5 to which the dredge has swung, as practical, thrust it into the earth, and raise the bridge spud out of its anchorage; then, reverse the screw device 28, so as to separate the said two spuds. The auxiliary spud being thrust 10 into the mud and the bridge spud raised, will cause that end of the bridge-frame to swing forward, pivotally on the other bridge spud, and to whatever distance it is so brought forward, it carries the dredge, bodily, by the 15 king-bolt just half the distance; the said operation being at the command of the operator. The auxiliary spuds may be both acted upon at the same time (simultaneously) and any other known mechanical means may be 20 employed to operate said auxiliary spuds attached to said bridge-frame and be within the scope of my invention. The machine is thus brought forward the desired distance for effecting another cut upon the excavation. 25 As the machine sweeps or swings to the other side, and has made its cut across the channel, the same manipulation repeated, moves the machine forward again.

To raise and lower the spuds, I prefer to use 30 the devices shown in my Patent, No. 299,945, dated June 10, 1884, and I derive the power to do so, and to drive the said gipsy and draper, or carrier, hereinafter described, from the engine C in the hull.

35 From the engine shaft, which is shown to be horizontal, a cog wheel meshes into the lower wheel on the vertical shaft 22, thence to the horizontal shaft 23 by gearing such as shown. At the end of shaft 23 nearest to the 40 king bolt is the miter wheel, which meshes into another miter wheel 24, the latter wheel being loose upon the said king bolt or shaft, collars being securely fastened on said king bolt or shaft, above and below the said miter wheel 24. Miter wheel 24 meshes into miter wheel 25, which is fastened to horizontal shaft 45 26. The shaft 26 is supported by a bridge frame and from it, the power can be transferred by belts or by shafting and gearing 50 as may be desired, by any well known mechanical means. The said bridge frame may be floated or carried partially or wholly upon scows or boats situated at each side of and 55 separate from the hull of the dredge, and such would be within the limits of my invention.

The improved draper or carrier I shown in Figs. 7, 8 and 9, is carried by sprocket wheels 32 with the chains 33 and 34. The sprocket wheels are on a horizontal shaft, one of them, 60 preferably, exactly over the king bolt and may be supported by any suitable framework.

In Fig. 8 it is shown that the links of the carrier chains from one joint to another are 65 duplicates and each link is composed of two separate parts 35 and 36 riveted together at their ends at each joint by rivets 37. Within each link is a wheel 38 which runs on a steel

rod 39 surrounded by a hollow pipe 40 said rod being thrust through holes in the sides of the links so as to reach through from one 70 outside face to the other.

In each link and alongside of the steel rods 39 just described is another rod 42 of the same construction, except that it does not extend through to the outside faces of said 75 chains, as it would obstruct the wheel from turning while the carrier is in operation; but said steel rod 42 can be pushed through any of said wheels while at rest, there being openings in them for that purpose. It will be observed that said hollow pipes on the two rods of each section of the chains are alike, and the steel rods differ only in respect to length. A piece of canvas, rubber belting, sheet iron or any other suitable material may form 80 pockets or buckets, by lapping one edge of said material over and around one of said pipes 40 (Fig. 9), and the opposite edge around the pipe 40 of the next link, so that when the side edges of the material are fastened to the 85 leg 43 of the inner links as shown at 44, a support for the pocket is made at the two sides and at the two ends. When one of these buckets or pockets is broken, a new one may be put into its place, without disconnecting 90 the said endless belt or chain carrier, by removing the pipes with the material composing the buckets or pockets and by replacing other pipes with the pockets already attached. 95

In Fig. 9, 45 represents a strip of wood, 100 which rests upon the two rods and their hollow pipes across the carrier from one chain to the other, being secured in place preferably by bolts connecting it with the leg or piece 43 upon each side, the means of attachment not being shown in the figure at each end. This strip is to cover, and prevent the dirt from getting between the hollow pipes, while each forms the edge of a section or pocket. A draper or carrier of this construction may be lengthened to as many such sections as may be necessary. It may be driven by power applied by any mechanical means, as by a belt upon pulleys 46.

I have devised novel means for attaching 115 the bucket of the dredging apparatus to the endless chains. (Shown in Figs. 4, 5, and 6.) Fig. 4 represents the position of the chains passing over the sprocket wheels, which is similar to the same as shown in my former 120 patent, No. 299,945, the sprocket wheels being omitted. Fig. 5 shows the front end of a bucket attached to the chains, the hangers 47 being firmly attached to the bucket of its forward end. In Fig. 4 the hangers 48 at the 125 aft end of the bucket is a pivot link, one end of which is sustained by the steel rod 49 passing through it and the other end on to a trunnion 50 which is fastened to the side of the bucket. This link is employed to keep the 130 bucket from being cramped by the chain while passing over the sprocket wheels. It also, when being at the aft end of the bucket, serves to push the aft end of the bucket out-

ward when passing around a curve and therefore adjusts the bucket cutting edge to its proper, and the same angle to the face of the excavation, as when the chains are passing 5 on a straight line.

What I claim is—

1. In a dredging apparatus, a swinging hull carrying dredging machinery, in combination with an anchored bridge frame to which said 10 hull is pivotally connected, substantially as set forth.

2. In a dredging apparatus, a swinging hull carrying dredging machinery, in combination with an anchored bridge frame to which said 15 hull is pivotally connected, and means substantially as described for swinging the hull upon said pivot.

3. In a dredging apparatus, a hull carrying dredging machinery, an independent bridge 20 frame pivotally connected to the hull and anchored at each side of the hull by removable spuds, in combination with two auxiliary spud frames pivoted at their inner ends at or near the center of oscillation, and means for 25 bringing pressure to bear upon either auxiliary spud frame, and thereby cause one end of the bridge frame and the hull bodily, to move forward.

4. In a dredging apparatus, the combination 30 of a hull, a bridge frame having anchoring spuds, and pivotally connected to the hull, a wheel or gipsy on the bridge frame,

and a chain or rope passing around said wheel or gipsy and having each of its ends connected rigidly to the hull, and means for 35 turning said wheel in either direction and thereby causing the hull to swing laterally independently of the anchored bridge frame, substantially as set forth.

5. An endless chain and bucket dredging 40 mechanism mounted upon a sweeping or oscillating support, and an inclined face ladder combined with rigid channel tracks, rollers or wheels within the chains arranged to run in the channel tracks whereby said buckets 45 are held to the work rigidly, and directed in a right line against vertical and lateral yielding, substantially as described.

6. In a dredging machine an endless carrier, comprising the endless chains composed 50 of divided links, transverse rods connecting the two chains and extending to the outside faces thereof, wheels journaled upon the rods between the arms of the divided links, and carrying sections secured to the rods, sub- 55 stantially as described.

In testimony whereof I have affixed my signature, in presence of two witnesses, this 19th day of December, 1891.

JOHN A. BALL.
